[57] CLAIM

The ornamental design for a hygienic sheath for a temperature sensing probe, substantially as shown and described.

DESCRIPTION

FIG. 1 is a front perspective view of a hygienic sheath for a temperature sensing probe, showing our new design;

FIG. 2 is a rear perspective view thereof;

FIG. 3 is a top plan view thereof;

FIG. 4 is a side elevation thereof;

FIG. 5 is a rear elevation thereof; and

FIG. 6 is a front elevation thereof.

The undisclosed bottom and side portions of the hygienic sheath are mirror images of the sides shown.
